(57) **CLAIM**

The ornamental design for a urine glucose meter, as shown and described.

DESCRIPTION

FIG. 1 is a front, left side, top perspective view of a urine glucose meter showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a reference front elevational view thereof showing a state in which this article is fold and a cap is attached;

FIG. 9 is a reference rear elevational view thereof showing a state in which this article is fold and a cap is attached;

FIG. 10 is a reference left side view thereof showing a state in which this article is fold and a cap is attached;

FIG. 11 is a reference right side view thereof showing a state in which this article is fold and a cap is attached;

FIG. 12 is a reference top plan view thereof showing a state in which this article is fold and a cap is attached;

FIG. 13 is a reference bottom plan view thereof showing a state in which this article is fold and a cap is attached;

FIG. 14 is a reference perspective view thereof showing a state in which this article is fold and a cap is attached; and,

FIG. 15 is a reference front elevational view thereof, showing a state in which this article is electrified.

The portions of the urine glucose meter in broken lines are shown for illustrative purposes only and form no part of the claimed design.
